UNITED STATES PATENT OFFICE.

SVEN J. STRID, OF CHICAGO, ILLINOIS, ASSIGNOR TO W. H. MINER, INC., OF CHICAGO, ILLINOIS, A CORPORATION OF DELAWARE.

DOOR-OPERATING MECHANISM FOR REFRIGERATOR CARS.

Application filed September 17, 1925. Serial No. 56,936.

This invention relates to improvements in door operating mechanism for refrigerator cars.

An object of the invention is to provide a door operating mechanism for refrigerator cars of simple design, wherein the shaft of the operating mechanism is given a rolling movement parallel to the face of the door, and wherein the shaft co-operates with keepers on the car, the keepers being designed to prevent rotation in a reverse or opening direction of the shaft due to vibrations of the car when in service, or to other causes.

Other objects and advantages of the invention will more clearly appear from the description and claims hereinafter following.

In the drawings, forming a part of this specification, Figure 1 is a side elevation of a portion of a refrigerator car, showing the door thereof and my improvements in connection therewith. Figure 2 is a horizontal, sectional view, partly broken away, corresponding substantially to the line 2-2 of Figure 1. And Figure 3 is a horizontal, sectional view on an enlarged scale, corresponding to the upper plane of the lower door keeper, showing the keeper in plan.

In said drawings, 10 and 11 designate hinged refrigerator car doors, the latter being the last one to be closed, said doors being provided with beveled meeting edges as indicated at 12 in the usual manner, and suitable packings are provided on said meeting edges and also around the outer edges 35 of the doors and door frame. As is customary, the operating shaft is mounted on the last door to be closed, that is, the door 11 in the structure as shown. The doors 10 and 11 are swingingly supported on the usual hinge members 12-12.

The improved door operating mechanism comprises, broadly, a shaft A; a pivoted operating handle B; a pair of guide brackets C-C; and a pair of keepers D-D.

The operating shaft A, as shown, comprises an intermediate connecting bar 13 of rectangular cross-section, end castings 14-14 and gear wheel castings 15-15. Each end casting 14 is forked as indicated at 16 to receive the corresponding end of the operating bar 13 and is secured to the bar by rivets extending through the forked portion and the casting. At the outer end, each end casting is of cylindrical cross-section, 50 as indicated at 17, thereby providing end

members adapted to co-operate with the corresponding upper and lower keepers D. Intermediate the ends thereof each member 14 is formed of angular cross-section as indicated at 18. Each gear member comprises 60 a gear proper 19 and a sleeve section. The gear proper and the sleeve section are provided with a rectangular opening adapted to receive the corresponding rectangular section 18 of one of the end members 14. It 65 will be evident that by providing the gear members with rectangular openings adapted to receive the corresponding rectangular sections of the end members relative rotation of the gears and end members is prevented. 70 In order to retain the gear members in fixed position against longitudinal movement on the end members, the same are preferably pinned to the latter as shown in Figures 1 and 2. The operating shaft is supported 75 and guided by the upper and lower guide brackets C, each of which comprises two members 20 and 21. The member 20 is in the form of a flat plate having a longitudinally disposed rack 22 at the inner edge 80 thereof. The member 21 of each bracket is in the form of a strap having a longitudinally disposed, central section 23 spaced from the plate 20 so as to provide a longitudinal guide for the corresponding end member 14. 85 At the opposite ends, the strap 21 is provided with inwardly extending lugs 24-24 by which it is secured to the plate 20. As shown in Fig. 2, the plate 20 and strap 21 are preferably held together and secured to 90 the door by a pair of bolts extending through the lugs 24, plate 20 and the door proper. A central guiding bracket in the form of a strap 25 may also be provided as shown in Fig. 1 to co-operate with the rectangular section 95 of the operating shaft A.

Secured to the lintel and threshold of the door opening are keepers D-D hereinbefore referred to, each of which has a pair of elongated parallel walls 26 and 27 extending at an angle to the plane of the side of the car. At the inner end of the keeper the side walls are offset as indicated at 28 and 29, these offset portions being substantially parallel to the plane of the side wall of the car. The wall sections 26-28 and 27-29 define a camming guide slot which co-operates with the cylindrical portion of the corresponding end member 14. Each keeper D is fixed to the side of the car by 100 105 110

bolts 30 extending through flanges 31 and 32 on the keepers, the flange 31 of the lower keeper being extended beyond the meeting edges of the doors and having a pivoted 5 latch member 33 mounted thereon adapted to co-operate with a wear plate 34 fixed to the corresponding lower corner of the door 10.

The operating shaft A is provided with 10 the usual pivoted handle member B for rotating the same, the handle B being preferably pivoted to the rectangular section 13 of the shaft.

In mounting the operating mechanism on 15 the door, the end members 14 of the shaft A are fixed to the bar 13 and the gear members 15 secured to the end members 14 before the operating shaft is mounted on the door. After the shaft A has been placed in position, 20 the plates 20 of the brackets having first been secured on the door, the straps 21 are placed in position and bolted to the plates 20 and the door.

The operation of my improved door operating mechanism is as follows, assuming the parts in the position shown in Fig. 1. The shaft A is rotated by pulling the handle B outwardly away from the door. Due to the gears 15 meshing with the racks 22, the 25 shaft A will roll along the surface of the door. During this movement of the shaft, the end portions 17 thereof will be brought into engagement with the inclined walls 26 of the keepers D, thereby camming the door outwardly as the shaft is rolled along. This 30 action will continue until the cylindrical ends 17 of the shaft leave the slots of the keepers as indicated in dotted lines in Fig. 3, whereupon the door may be freely swung to open position. It will be evident that 35 during the opening operation the shaft A will be rotated through an angle of 180° bringing the handle B into flat engagement with the outer side of the door 11 in a position opposite to that shown in Fig. 1. To close the door, the same is swung inwardly until the upper and lower cylindrical ends 40 17 of the shaft are brought into alinement with the entrance to the slots in the top and bottom keepers D. Upon swinging the 45 handle outwardly, the shaft A will be rotated in the opposite direction to that hereinbefore described, effecting a rolling movement of the shaft in a reverse direction to that which it had during the door opening operation. During its rolling movement, the end portions of the shaft will cam on the inclined walls 27 of the top and bottom 50 keepers, thus causing the door to be forced inwardly. This action will continue until the end portions of the shaft roll onto the straight walls 29 of the keepers. In this 55 position, the door will be tightly closed. A slight further movement of the handle to bring it into the position shown in Fig. 1,

will cause the cylindrical ends to move inwardly on the walls 29 a sufficient distance to prevent accidental disengagement of the end members with these walls, this position being indicated in the full lines in Fig. 3. 70 Inasmuch as the walls 29 of the keepers are parallel to the outer side of the car and also parallel to the plane of the outer surface of the door 11, when fully closed, there will be no tendency for the shaft to have an accidental retrograde movement. In other words, the outwardly acting forces, when the doors are closed, due to the end sections 17 of the shaft engaging the walls 29 will not have any components which act in 80 lateral directions.

While I have herein shown and described what I now consider the preferred manner of carrying out my invention, the same is merely illustrative, and I contemplate all 85 changes and modifications that come within the scope of the claims appended hereto.

I claim:

1. A device of the character described, the combination with a member having a door opening and a door; of means for effecting movement of the door in opening and closing directions including an operating shaft mounted on the door; a keeper comprising a portion adapted to be secured to said member and including spaced substantially parallel walls defining a cam slot open at one end to permit entrance and retraction of an end portion of said shaft to said cam slot, the major portions of both of said parallel walls 90 extending at an angle to the plane of said member, and the remaining portions of both of said walls extending parallel with the plane defined by said member. 95

2. As an article of manufacture, a keeper comprising a flat portion adapted to be secured to a door member and including parallel walls defining a cam slot open at one end to permit entrance and retraction of a door operating member the major portions 105 of both of said walls extending at an angle to said flat portion, and the remaining portions of both of said walls extending parallel with respect thereto. 110

3. As an article of manufacture, an elongated keeper comprising a portion to be adapted to be secured to a door member, and including spaced substantially parallel walls and a bottom wall defining a cam slot having the major portion thereof inclined toward 115 said flat portion, and another portion extending substantially parallel with respect to said flat portion, the extremities of said walls remote from said flat portion terminating to provide an entrance to said cam slot. 120

4. In a device of the character described, the combination with a member having a door opening and a pivoted door; operating mechanism on said door, including a rotary shaft projecting beyond the edge of the 130

- door, and co-operating devices on the door and shaft for causing the latter to roll transversely of the door in a plane substantially parallel with the plane defined by the face 5 of said door when said shaft is rotated; and keeper means adapted to co-operate with the projecting end of said shaft for effecting movement of said door in opening and closing directions, said keeper means comprising 10 a portion adapted to be secured to said member and including spaced substantially parallel walls defining a cam slot open at one end to permit entrance and retraction of the projecting end portion of said shaft with 15 reference to said cam slot, the major portions of both of said parallel walls extending at an angle to the plane defined by the face of said member, and adapted when traversed by the shaft end to effect opening and closing movement of said door, the remaining portions of both of said walls extending 20 parallel with the plane defined by the face of said member and adapted for the reception of the shaft and following the movement of the door in a closing direction to maintain 25 said shaft against accidental movement in a door opening direction.

In witness that I claim the foregoing I have hereunto subscribed my name this 9th day of September, 1925.

SVEN J. STRID.
